REFLECTOR BUTTON UNIT

John R. Wald and Gilbert Rodli, Huntingdon, Pa.

Application May 24, 1937, Serial No. 144,536

5 Claims. (Cl. 88—82)

The present invention relates primarily to reflector buttons of the reflex reflecting type, such as are commonly used to form indicia for warning motorists, giving directions, etc. More specifically, this invention has especial relation to combined reflector and retainer means for reflector buttons of the aforementioned character. The present invention relates further to the use of synthetic resinous materials, such as the methyl methacrylate resins and the like, for making the said reflector buttons.

Signs comprising a studding of reflector buttons are well known to every motorist; perhaps the most familiar type of sign of this type is the "stop" sign appearing at intersections for the purpose of controlling the traffic entering a thoroughfare. Such signs generally consist of a colored disk on an upright post with reflector buttons embedded in the surface of the disk in such a way that a beam of light directed against the sign at night will cause the reflection of the word "stop" in brilliant letters. In the day-time, the word is, of course, apparent without the use of a light beam.

It is with a sign of this general type that the present invention is most advantageously employed, although, as stated above, the invention can well be used on a multitude of different types of signs and indicia.

The known signs are efficient when first installed, but after exposure to the elements for a comparatively short time, the reflector buttons seem to lose their brilliance. The result is that the sign must be replaced from time to time. It has been discovered that the reason for the degeneration of such signs lies in the fact that the mountings of the buttons are so constructed that air finally reaches and corrodes the surface of the reflector element.

40 In one form of button and mounting therefor, according to the prior art, the mounting or retainer consists of a cup-shaped receptacle in which is arranged a glass button. The bottom of the receptacle or of the glass button is provided with a coating of reflecting material. Access of air and/or moisture to the latter causes the degeneration above referred to.

45 In a second form of reflector button proposed by the prior art in an attempt to obviate the above-mentioned defect of corrosion and deterioration of the reflector surface, the reflector element is embedded in the glass material of the button. However, the temperature necessary for the molding of the glass has been found to adversely affect the reflector element. Moreover, it

has further been found that a small quantity of air remains between the said reflector element and the glass button and eventually dulls the reflecting surface.

Another disadvantage of the known signs is the fact that the retainer for the button and the reflecting element are formed of two separate pieces of material, with the result that it is relatively difficult to handle the retainer, the reflector, and the button while assembling them in place on the surface of the disk.

The present invention, which obviates the above-discussed defects, consists of a one-piece reflector and retainer in combination with a button formed, not of glass, but preferably of a synthetic resin. By using a one-piece reflector and retainer, assembling of the button on the sign is substantially simplified.

While various of the many available synthetic plastic or resinous materials, such as the urea resins, the amine-formaldehyde resins, etc., may be used according to this invention, the preferred resins are those of the methyl methacrylate type (known in the trade as "Lucite").

An important advantage of this invention is the fact that the material of which the button is made, according to the invention, is much lighter and can be molded much more easily than glass. There are many other advantages incident to such a use of resin such as "Lucite" or the like, as will hereinafter appear.

The foregoing and other features of the invention will be best understood and appreciated from the following description of preferred embodiments thereof in which the application of the invention to the "stop" type of sign is set forth and illustrated in the accompanying drawing, wherein:

Fig. 1 is a partial front view of a completed sign, according to the invention;

Fig. 2 is a cross section of part of the sign and one of the buttons;

Fig. 3 is a cross section taken along line 3—3 of Fig. 2;

Fig. 4 is a cross section of another embodiment of button according to the invention;

Fig. 5 is a bottom plan view of the embodiment shown in Fig. 4;

Fig. 6 is a cross section taken along line 6—6 in Fig. 5;

Fig. 7 is a cross section of a third embodiment of the invention;

Fig. 8 is a cross section taken through still another form of this invention; and

50

45

55

Fig. 9 is a bottom plan view of the form shown in Fig. 8.

Corresponding reference characters are used to designate corresponding elements throughout the drawing.

Referring first to Figs. 1, 2 and 3 of the drawing, a sign according to the present invention may consist essentially of a supporting element, such as a sign post 10, a sign housing 11 mounted thereon, and indicia constituted by reflector buttons 12 on the front of said housing.

As shown more particularly in Figs. 2 and 3, housing 11 may be composed essentially of a back member 13, a false back 14, and a front member 15. The periphery of either the front or back member may be bent over to form the rim of the housing. Any suitable and conventional means may be provided for retaining the false back 14 in the relative position shown on Figs. 2 and 3 of the drawing.

False back 14 is provided with a plurality of relatively small openings 16 arranged according to the indicia to be defined. The front member 15 is provided with a corresponding set of relatively large openings 17, as shown. The front member 15 is preferably removable from the backing members 13 and 14.

The several reflecting elements according to the present invention may preferably consist of a reflector button proper 12 and a combined reflector and retainer member 18, 19, the reflector portion 18 of which is wholly embedded in the material of the button, while portions of retainer member 19 project from the bottom of the button 12 as shown.

Considering, specifically, the combined reflector and retainer member 18, 19, the reflector portion 18 may assume the form of a hollow semi-spherical metallic member, arranged as shown in Figs. 2 and 3, i. e., with its inner concave surface toward the front of the button. This surface may be made, for example, of brass or steel or the like, and the said inner concave surface is provided with a suitable and conventional reflector coating, e. g., by silvering or by chrome plating or in any other desirable manner.

Integrated with member 18 at the bottom of the exterior surface thereof is the retainer member 19. This consists essentially of a central body portion associated with the reflector member 18 by brazing, welding or the like, and a pair of downwardly-extending resilient arms or fingers 20.

In associating the button 12 and its combined reflector and retainer by molding at elevated temperature, the latter are preferably positioned in such manner that in the final product the reflector element 18 is totally embedded in the button while the spring arms 20 extend downwardly from the bottom thereof. As shown in Figs. 2 and 3, the button itself may preferably be given a substantially ovate configuration.

When assembling the sign, each button 12 is first made fast to the false back 14 by means of the spring fingers 20 which are sprung into place in the corresponding opening 16. The arcuate form of the fingers and their resiliency keep the buttons securely in place. The front member 15 is then mounted in position over the buttons 12 which project severally through the corresponding openings 17. The material around each opening 17 may be embossed, as shown, so that each button 12 is embraced tightly by the front member 15 at a point beyond the line of maximum diameter of the button. Thus, with the front

member in place, the buttons are firmly retained in position thereby as well as by the retainer member 19.

As hereinbefore stated, buttons 12 may preferably be made of resinous material of the methyl methacrylate type, i. e., a resinous polymerized derivative of methacrylic acid, also known as "Lucite".

This material has been found to be particularly suitable for the purposes of the present invention. Thus, due to its low specific gravity as compared with glass, for instance, the resulting sign will be appreciably lighter. Cost of transporting the buttons is also materially reduced.

"Lucite" contains no volatile solvents which will cause shrinkage by evaporation, so that there is no shrinking thereof away from the embedded reflector element upon cooling after molding.

The new resinous material shows substantially no water absorption when exposed to normal weather conditions. Moreover, it will not age or discolor when exposed to sunlight, and is substantially unaffected by ultra-violet light.

The molded material can be readily machined, e. g., on a lathe or the like, to desired configuration.

The molding temperatures of the new material are particularly advantageous ranging from about 285° F. to about 315° F.

As hereinbefore set forth, other known, suitable and desirable resinous compositions may also be used in making buttons 12.

Referring now to the modification of the invention shown in Figs. 4, 5 and 6 of the drawing, it will be seen that according to this embodiment the button 21 preferably assumes the configuration of a headed bolt, the shank portion of which is inserted through an opening 17' provided in supporting or front member 15'. In this form of the invention, the front member 15' is preferably fixed and is associated in any desirable and conventional manner with a removable rear member (not shown). No false back need be employed.

The combined reflector and retainer according to this second modification is made up of a substantially circular reflector portion 22 which, as shown, is wholly embedded in the material of the shank of the button 21, and of a plurality of fingers 23, 24 which radiate from said reflector portion 22. Alternate fingers 23 are longer than the intermediate fingers 24 and are bent as shown to impart resilience thereto.

Fingers 23 and 24 extend upwardly along the shank portion of the button 21, projecting laterally from the latter adjacent the bottom thereof. When snapped into place on member 15', fingers 24 assume the position shown in Fig. 6 whereby outward displacement of the button is prevented, the length of fingers 24 being preferably adjusted so that the ends thereof abut the rear surface of plate 15'.

Fingers 23, on the other hand, assume the position clearly shown in Fig. 4, these fingers being of such length that the ends thereof extend into opening 17', whereby transverse "rattling" of the buttons is effectively prevented.

To remove or replace a button, the back member is removed and the fingers are compressed by means of a suitable clamping tool whereby the fingers are positioned so that they may be slipped through opening 17'.

Button 21 is preferably made of "Lucite", or any other suitable and desirable resinous com-

position, and member 22 is provided with a reflecting surface on its outwardly facing side. The parts are so related that the head of the button rests firmly on the outer surface of plate 15' when in place.

5 A third embodiment of the invention is shown in Fig. 7. In this form the combined reflector and retainer is made up of an embedded reflector portion 25, 26 and integral fingers 27 extending therefrom. These fingers project laterally from the shank of bolt-shaped button 21 adjacent the top part of the shank, being bent back downwardly along the latter. Each finger 27 is resilient due to its configuration.

10 The reflector portion comprises a central part 25 which corresponds essentially to reflectors 22 and 18 of the afore-described embodiments. Portion 26, extending between member 25 and the radially projecting fingers 27, may be substantially cylindrical in form, and the inner surface thereof may preferably also be provided with a reflecting coating.

15 The button unit, including the integral reflector and retainer, is snapped into place from the exterior of plate 15', fingers 27 being contracted during inward movement and springing out into the arrangement illustrated. The upper portions of fingers 27 abut the edge of opening 17', preventing transverse displacement of the button 20 tons.

20 A compressing tool may be employed from the rear when removal of the buttons is to be effected, the rear plate (not shown) associated with plate 15' being removable as in the preceding embodiment.

25 A further form of the invention is shown in Figs. 8 and 9, wherein the resinous button 28 is also of the bolt type so that it comprises an exposed head portion and a shank portion. The 30 combined button retainer and reflector may, according to this embodiment, consist of a totally embedded dished reflector portion 29 integrated with a plurality of arms 30 extending therefrom to the exterior of the button.

35 The shank of the button is preferably provided with a plurality of longitudinally extending recesses 31 corresponding in number to the number of arms 30, each recess being adapted to receive its corresponding arm.

40 In this form of the invention, the maximum outer diameter of the button shank is substantially the same as the diameter of opening 17'. Upon inserting the buttons 28 in plate 15', the 45 retainer arms 30 are forced into recesses 31 until the rear of the head of button 28 is seated against plate 15', whereupon arms 30 spring outwardly to the position shown in Fig. 8. A suitable arm compressing tool may be used to effect removal of the buttons from the supporting plate.

50 Having thus described the invention, what is claimed as new and is desired to be protected by Letters Patent of the United States is:

55 1. A reflector unit of the reflex reflecting type consisting of a solid molded button of synthetic resinous material and a combined reflector and retainer therefor, said combined reflector and retainer comprising a reflector element wholly embedded in and surrounded by said material and a retainer element joined to said reflector element in integral relationship therewith, said retainer element including resilient retaining fingers extending from the material of said button.

ton, said reflector element having a plurality of surfaces including a reflecting surface, and said synthetic material being in intimate contact with all said surfaces.

2. A reflector unit of the reflex reflecting type 5 consisting of a solid molded bulbous element of synthetic resinous material of the character of polymerized methyl methacrylate and a combined reflector and retainer therefor, said combined reflector and retainer comprising a reflector element entirely embedded in and surrounded by 10 said material and a retainer element joined to said reflector element in integral relationship therewith, said retainer element including resilient retaining fingers projecting rearwardly from 15 said bulbous element, said reflector element having a plurality of surfaces including a reflecting surface, and said synthetic material being in intimate contact with all said surfaces.

3. A reflector unit of the reflex reflecting type 20 consisting of a solid molded synthetic resinous button and a combined reflector and retainer therefor, said button including a body portion having a substantially circular cross section, said combined reflector and retainer comprising a reflector element wholly embedded in and surrounded by the material of said button and a retainer element integral with said reflector element and including resilient retaining fingers extending laterally from the body portion of said 25 button, said reflector element having a plurality of surfaces including a reflecting surface, and said material being in intimate contact with all said surfaces.

4. A reflector unit of the reflex reflecting type 30 consisting of a solid molded synthetic resinous button and a one-piece reflector and retainer therefor, said button being substantially bolt-shaped and including a head and a shank extending from said head, said reflector and retainer comprising a reflector element wholly embedded in and surrounded by the material of said shank and a retainer element including resilient retaining fingers extending laterally from said shank adjacent one end thereof, said reflector element having a plurality of surfaces including a reflecting surface, and said material being in intimate contact with all said surfaces.

5. A reflector unit of the reflex reflecting type 35 consisting essentially of a solid molded synthetic 50 resinous button and a combined reflector and retainer therefor, said button being substantially bolt-shaped and including a head and a shank extending from said head, said combined reflector and retainer including a reflector element wholly 55 embedded in and surrounded by the material of said button and a retainer element integral with said reflector element and including resilient retaining fingers extending laterally from said shank adjacent the bottom thereof, said shank 60 being provided with a plurality of longitudinally extending recesses, the number of which corresponds to the number of said retaining fingers, said recesses being adapted to wholly receive said fingers during mounting and dismounting of the 65 unit, said reflector element having a plurality of surfaces including a reflecting surface, and said material being in intimate contact with all said surfaces.
